WINDING COP

Wilhelm Reiners and Gustav Kahlisch, Gladbach-Rheydt, Germany, assignors to W. Schlafhorst & Co., Gladbach-Rheydt, Germany, a corporation of Germany

Application November 7, 1933, Serial No. 697,056
In Germany November 22, 1932

8 Claims. (Cl. 242—18)

In connection with spinning and twisting machines it has been proposed to attach the yarn or thread, when the cop has been wound, either to the cop tube at the foot thereof or to the spindle, the attachment being, however, only effected by allowing a few turns to run on to the tube or spindle, without fastening the same. The purpose of doing this is to prevent yarn from slipping off the tapered end of the cop. This method of securing the yarn or thread is, however, not applicable to winding machines, as for instance those used for winding on tapered bobbins, especially where the material to be wound is of a slippery kind,—such as artificial silk yarn and the like, inasmuch as the coils of yarn would slip off the base of the cop tube, or the spindle, and become unwound when the cop is withdrawn from the spindle.

For fastening the end of the yarn, notches have in some cases been made in the foot of the cop tube, and the end of the yarn has been engaged with said notches by hand.

The object of our invention is to effect attachment of the yarn by mechanical means, in connection with winding machines, in such a manner that the yarn will neither slip off the tube nor escape from the thread guide.

We may effect this in various ways, for instance, by causing the thread guide, when the cop has been wound, to move rapidly from the head of the cop tube to the foot of the latter, so that only a few turns of coarse pitch are laid on the cop, till the guide reaches the foot of the cop tube, where it allows one or two turns to be made, then proceeding alongside the bare spindle, or to the hub of the spindle, where some more turns are wound on.

An alternative method consists in attaching the yarn, after the cop has been completed, by means of a few close turns first at the tip of the cone, either on the cop itself or on the cop tube, or on a specially provided holder, which may include a rubber ring or a spring loaded cap, the yarn being then carried along the cop, on which it makes a few steep turns, and in some cases a few close turns, before being carried to the foot and to the spindle itself. Another method consists in carrying the yarn back along the cop, making a few steep turns, and then taking it to the hub of the spindle, where a few more turns are made. Before passing from the foot of the tube to the spindle the yarn is engaged with notches or projections provided in or on the foot for that purpose.

In all cases the yarn is mechanically secured

in at least two places successively after the cop has been completed. It may be gripped at the foot of the tube before leaving the foot in order to be wound on the spindle, or the gripping may be effected when the cop is withdrawn from the spindle. Securing the yarn to the spindle ensures that it remains in engagement with the thread guide, so that when an empty cop tube has been placed on the spindle the yarn may be immediately engaged therewith and the winding of a fresh cop started.

The waste thread wound on the spindle is cut away from time to time by hand, or by a knife or the like, and this may be effected mechanically by a cutter carried by the spindle. A removable ring or collar on which the yarn is wound may be placed on the spindle to facilitate the removal of the yarn.

Examples illustrating the invention are shown in the accompanying drawings, in which:—

Fig. 1 is a side elevation of a cop wound in accordance with the invention.

Fig. 2 is a side elevation of a cop wound in a different manner with holding turns at the tip of the cop.

Fig. 3 is a side elevation of a different embodiment of the invention, including a group of holding turns intermediate the tip and base of the cop.

Fig. 4 shows a modification of Fig. 1 with different means for anchoring the thread on the base of the cop tube.

Fig. 5 shows a cop which is wound in the manner shown in Fig. 4 withdrawn from the spindle.

Figs. 6 and 7 show in side and front elevation respectively a spindle with a groove in the hub for securing the yarn.

Fig. 8 is a side view of a resilient ring placed on the spindle hub for holding the yarn, the ring having a series of apertures through which a knife blade may be inserted to cut the yarn wound on the ring.

Fig. 9 shows a spindle with a hub having a grooved edge to prevent unwinding when the cop tube is withdrawn.

Fig. 10 is a side elevation of a spindle with a mechanism for cutting the turns of thread on the spindle at intervals.

Fig. 11 is a view corresponding to Fig. 10 showing the cutting members moved in.

Fig. 12 is a plan view of Fig. 10.

Fig. 13 is a side elevation of a supplementary manually operated winding mechanism for securing the thread on the cop tube and the spindle in accordance with the instant invention.

In all the views, 2 designates the cop tube, 1 the cop, 3 the peg of the spindle, 4 the spindle hub, 6 the thread guide and 7 a bar carrying a number of thread guides supported by guide rods 8 and reciprocated in the direction of the spindle axis.

Referring to Fig. 1, when the cop is completed, the thread guide 6 moves the yarn rapidly away from the cop cone to the gripping groove 9 at the foot of the cop, so that a few steep convolutions of yarn 21 are wound on the cop and the yarn is held fast in the groove by a few turns 22 therein. The thread guide 6 may be controlled manually in a manner well known in the art as explained below. The thread guide then conducts the yarn to the concavely shaped part 5 on the spindle hub 4 and a few turns 25 are wound here. To prevent these from becoming unwound when the cop is withdrawn from the spindle, the edge 29 of the spindle hub 4 is either provided with a plurality of notches 26, as shown in Figures 6, 7, or is grooved to present a rough surface as shown in Figs. 4, 5 and 9. The yarn clings to these grooves or to the roughened surface when the cop is withdrawn and the yarn is broken between the cop and the edge 29 when the cop is removed from the spindle.

Referring to Fig. 2, when the cop is completed a few close turns 23 are wound on the cop or cop tube at the tip thereof. The thread guide 6 then rapidly carries the yarn in the form of a few turns 21 to the point 9 at the foot of the cop tube, where it is held fast by a few turns 22, the yarn then passing to the spindle hub as above described.

Referring to Fig. 3, the yarn in addition to being held fast at the tip of the cop or cop tube, is also held fast in one or more places on the cylindrical part of the cop, by windings 24, this being particularly advantageous in the case of slippery yarn or thread. The yarn is then passed to the foot of the cop and thence to the spindle hub and secured by means of several convolutions, as described with reference to Figs. 1 and 2.

Referring to Fig. 4, when the cop has been wound the thread is again caused to make a few turns 21 on its way to the foot of the cop, and is then passed to the spindle hub, where it is held by a few convolutions 25 in the manner above described. In passing from the foot of the cop tube to the spindle hub the yarn is gripped in the grooves or notches in the cop tube, so that it is prevented from slipping off.

55 The grip devices at the foot of the cop may be of various forms.

To enable the yarn wound on the hub of the spindle to be readily removed, said hub may, as previously mentioned, be provided with notches 26, and the coils of yarn may be cut by introducing the blade of a knife, as shown in Fig. 6. This method is also applicable with a perforated ring on the spindle hub 4, as shown in Fig. 8, the yarn being wound on this ring as shown at 25, and the knife blade being inserted between the apertures. If desired, the perforated ring with the coils thereon may itself be drawn off the spindle hub.

To remove the coils 25 from the spindle hub 4 by mechanical means the device shown in Figs. 10 and 11 may be employed. This device comprises a hopper 30 underneath the winding at 5 and communicating with a suction fan 31. 31 is an annular carrier for a cutter 38 slidably arranged on the spindle, said cutter engaging in

one of the notches 26 in the spindle hub. 39 is a spring disposed between the cutter carrier 37 and the spindle hub, and is adapted to restore the cutter to its normal position after operation. Arranged in front of a number of carriers 37 is a flanged bar 32, the vertical flange of which is provided with slots engaging the spindles. The bar 32 is carried by guide rods 33, which are provided at their ends with teeth meshing with pinions 34 mounted on a shaft 35. On the shaft 10 is a lever 36, which is adapted to rotate the shaft. 40 designates the spindle bearing, 41 the pulley for driving the spindle and 42 the driving shaft carrying the pulley 41. Clockwise rotation of the shaft 35 causes the bar 32 to be moved to the right, so that all the coils 25 on all the spindle hubs are cut by the cutter 38, the cuttings dropping into the hopper 30, which are conducted away by the suction of the fan 31.

Figure 13 shows an embodiment of the apparatus, whereby at the end of the winding of the spool a hastened movement of the thread guide is effected for the purpose of producing a thread spiral 21, and upon the conclusion of the spiral, for winding several turns upon the base of the 25 bobbin tube at 9 and upon the spindle at 25. This mechanism is fully described in our copending application, Ser. No. 618,554, filed June 21, 1932.

The thread guides 6 are mounted upon a common rail or bar 53 which is carried by toothed bars 54, shiftably mounted along the spindle axis. The movement of the bars 54 is effected by means of gear wheels 55 mounted upon shaft 56. Two chain rollers or sprockets are mounted upon shaft 56, one of which is behind gear wheel 55 and which is connected with the chain 46, which is also fixed upon a sprocket mounted in the lever 57. Upon the shaft 58 of the sprocket is mounted a worm wheel 50 which meshes with another worm wheel 51 also mounted in lever 57. A hand wheel 45 in the form of a ratchet wheel, having a handle 44, is mounted upon the axle of the last-mentioned worm wheel 51.

The sprocket 48 shown in Fig. 13, mounted upon the shaft 56, is provided with a chain 47 which is loaded by weight 52 for the purpose of enforcing the to and fro movement of the gear wheels 55.

The operation of the illustrated arrangement is as follows:

When the spools 1 of a combined group of spindles 3 are completely wound up and the winding machine is at a standstill, the catches 45a are taken out of the teeth of the ratchet 45, to permit of the thread guide 6 being moved into any desired position with regard to the spindles, for instance a stationary position 23a (Fig. 13) in order to wind-on a bunch 23 (Figs. 2 and 3) by simply turning the handle of the hand-wheel 43 (Fig. 13) in order to revolve the spindles 1. By continuing this movement of turning the handle and simultaneously turning also the handle 44 of the ratchet 45 in clockwise direction, the helical wheel 51 turning the helical wheel 50 in such a fashion that the weight 52 causes the thread guides to be slowly traversed along the spindles 1, the two combined motions will evidently cause a spiral 21 to be placed on the spool 1. This formation of the spiral can be interrupted at will by the formation of another bunch 24 at any place, if for this purpose the turning of the handle 44 is momentarily stopped whilst the turning of the handle on the hand wheel 43 continues. By subsequently turning both handles again simultaneously, the spiral 75

may be continued until the yarn guide arrives at a point 9 where a bunch 22 may again be formed in the same fashion as described for the bunches 23 and 24. In a similar fashion, the handles are manipulated in order to obtain a spiral between bunches 22 and 25, and finally the bunch 25 itself. Thereby a mechanical fixation of the thread is obtained.

It is understood that it is possible to fix the thread automatically by suitable mechanisms rather than by manual means such as described above.

We claim:—

1. In an apparatus of the class described, a winding spindle, a cop tube on said spindle, means for rotating said spindle, a thread guide movable along said spindle for guiding the thread onto said cop tube in the course of the winding operation, means for anchoring the thread on the cop tube at the conclusion of the winding operation comprising means for retaining holding turns of thread on the finished cop and an element for positively catching the thread at the base of the cop tube, and a shaped portion on said spindle for receiving a plurality of holding turns of the thread.

2. The apparatus as defined in claim 1 wherein the shaped portion on the spindle is formed resiliently.

3. The apparatus as defined in claim 1 wherein the shaped portion on the spindle is in the form of a resilient ring which is detachably mounted on the spindle.

4. In an apparatus of the class described, a winding spindle, a cop tube on said spindle, means for rotating said spindle, a thread guide movable along said spindle for guiding the thread onto said cop tube in the course of the winding operation, means for anchoring the thread onto the cop tube at the conclusion of the winding

operation comprising means for retaining holding turns of thread on the finished cop comprising a plurality of turns at the base of the cop tube, a shaped portion on said spindle for receiving a plurality of turns of the thread, and a roughened edge on said spindle between said shaped portion and the base of the cop tube for catching the thread at said edge.

5. In an apparatus of the class described, a winding spindle, a cop tube on said spindle, means for rotating said spindle, a thread guide movable along said spindle for guiding the thread onto said cop tube in the course of the winding operation, means for anchoring the thread onto the cop tube at the conclusion of the winding operation comprising means for retaining holding turns of thread on the finished cop comprising a plurality of turns at the base of the cop tube, a shaped portion on said spindle for receiving a plurality of turns of the thread, and a grooved or notched edge on said spindle between said shaped portion and the base of the cop tube for holding the thread at said edge.

6. In an apparatus of the class described, a rotatable winding spindle having a peg for supporting a cop tube and a resilient portion for receiving a plurality of turns of thread.

7. In an apparatus of the class described, a rotatable winding spindle having a peg for supporting a cop tube and a hub, and a resilient ring detachably mounted on said hub for receiving a plurality of turns of thread.

8. In an apparatus of the class described, a rotatable winding spindle having a peg for supporting a cop tube and a shaped portion adjacent said peg for receiving a plurality of turns of thread, and a grooved or notched edge between said shaped portion and peg for retaining the thread.

WILHELM REINERS.
GUSTAV KAHLISCH.
